RATION OF WISCONSIN.

APPARATUS FOR DRYING AND SHAPING HOSIERY AND THE LIKE

1,114,966.

Specification of Letters Patent.

Patented Oct. 27, 1914.

Application filed June 27, 1911. Serial No. 635,686.

To all whom it may concern:

Be it known that I, GEORGE COLLIS, a citizen of the United States, residing at Dubuque, in the county of Dubuque and State of Iowa, have invented certain new and useful Improvements in Apparatus for Drying and Shaping Hosiery and the like, of which the following is a specification, reference being had therein to the accompanying drawing.

My invention relates to apparatus for drying and shaping textile articles (such as hosiery, and the like), and has for an object the provision of instrumentalities whereby one or more of the articles may be supported in a manner to facilitate the presentation thereto of a suitable drying medium—in the form of heat, hot air, steam, etc.—the application of said drying medium being either to the interior surface of the article or to both the interior and exterior surfaces simultaneously, whereby evaporation of the moisture in the article may be effected with celerity and uniformity, and whereby also the proper shaping of the article may be simultaneously produced.

In hosiery mills, the usual methods of drying and shaping hosiery practised at the present time include the placing of each stocking upon a thin solid wooden board. Several of these are then mounted on a rack or similar structure and moved into a drying-room, to be left there sufficiently long to permit drying of the stockings. They are then withdrawn from the drying-room and, thereafter, removed from the boards. The next step is to shape them. This is done as a separate step and subsequently to the drying.

The aforementioned first step of "boarding", as it is termed, is slow and expensive, and the results are always uncertain, since the presentation of the heat is to the exterior surface only of the article, and the heat does not always penetrate through the fabric, so that, frequently, the articles are withdrawn from the drying room before their complete drying is effected. Moreover, the expense of maintaining the proper degree of heat in the drying-room is great, and, even where care is exercised, the temperature may vary considerably. The necessity of rehandling the articles for shaping them still further increases the labor and expense of manufac-

ture. By my invention, these objections and disadvantages are eliminated and the product is of a superior quality. Moreover, it is a desideratum simultaneously to dry and shape the article being treated. Thereby, the second step mentioned as characterizing present-day methods is entirely avoided. Moreover, by the instrumentalities included in the apparatus, I am enabled simultaneously to present heat both to the interior surface and to the exterior surface of the article, whereby a thorough drying of the article is insured.

The invention includes the apparatus, the mechanisms, the devices, and the elements hereinafter described. I desire to state, at the outset, however, that my invention is not restricted to the details now to be described, nor to the particular relative arrangement and aggroupment herein shown, except insofar as these may be specified in the claims.

In the accompanying drawings, wherein I have illustrated certain embodiments of my invention—though it will be recognized that other embodiments are within the spirit of the invention—Figure 1 is a view in sectional elevation of my improved hosiery-drying and shaping apparatus; Fig. 2 is a top plan view thereof, a portion of the structure being broken away more clearly to reveal parts of the machine; Fig. 2^a is a fragmentary view in horizontal section of a portion of the structure; Fig. 3 is a fragmentary view, also in plan, of a portion of the structure, on a somewhat larger scale; Fig. 4 is also a fragmentary view in sectional elevation, showing a part of one form of actuating mechanism of the machine; Fig. 5 is also a fragmentary view, in plan, showing the same; Figs. 6 and 7 are detail views of roller-devices forming a part of the frame-supporting structure; Figs. 8 and 9 are detail views respectively in elevation and horizontal section of the stocking-supporting member; Fig. 10 is a view, similar to Fig. 1, of a modified form of machine; Fig. 11 is a view, similar to Fig. 2, of this modified form of machine; and Figs. 12 and 13 are fragmentary views in front and side elevation of another modified form of machine, parts of the machine being shown in section.

Referring to these drawings, the reference-numeral 1 designates a table, base or ma-

chine-frame which includes a top-plate 2 and supporting standards or legs 3, 3, which may be of any suitable form but which, in this instance, are constructed with a view to affording strength and rigidity to the machine. Mounted above said top-plate is a carrier or member-supporting frame which is designated generally by the numeral 4. In the preferred embodiments of my invention, this frame includes a circular member or casting 5, a hub-structure 6 comprising an upper heat-supplying hub 7, and a lower heat-withdrawing hub 8. Extending between and connecting said hub-structures 10 and the circular member are a series of spokes or arms 9.

The aforementioned member-supporting frame 4 is designed to rotate, and, to this end, is movably supported on said base or table. To facilitate the rotative travel of said frame, there is interposed between the hub-structure 6 and said base an anti-friction bearing 10; and, similarly, there is interposed between the circular member 5 and the base a series of angularly-arranged rolling-elements or guides which, in this instance, are in the form of guiding rollers 11, each of which is suitably journaled in an up-standing yoke-member 12 adjustably secured 20 on a block 13 attached to the top-plate. To effect an adjustment of said roller, for the purpose of positioning it relatively to the lower surface of the circular member, an adjusting-screw 14 is threaded in said block 13 30 and engages the underside of said yoke-member 12. By turning said screw in one direction the yoke and its roller are raised; or if it is turned in the opposite direction, they are correspondingly lowered. To effect 35 rotative movement of said member-supporting frame, any suitable actuating-mechanism may be employed, and this may be driven from a source of power, or manually. In an embodiment herein shown, I have, by way of 40 example, disclosed a manually-operated mechanism for driving said frame; but it is to be understood that, in some instances, it would be advantageous to drive the same by power, as shown in Figs. 12 and 13.

50 The manually-operated mechanism referred to includes a slide 15 adapted to oscillate in a guide-way or block 16 mounted on the portion of the top-plate underlying the supporting frame. Pivoted at one end of 55 said slide 15 is a spring-controlled pawl 17 adapted to engage one or another of a series of abutments 18 mounted equidistantly on the lower face of the circular-member 5. Arranged in juxtaposition to said guide-block 16 and in the path of travel of the abutments is a spring-pressed safety-stop 19, the function of which is to engage one of 60 said abutments 18 and arrest the movement of the supporting-frame beyond a predetermined point. It will be observed that the

stop 19 is, at its upper end, beveled on the active face 19^a and that the active face or portion 18^a of each of the abutments is correspondingly beveled. In consequence, when the two beveled faces of these elements engage they will, under normal pressure, effect a stopping of the frame; but when abnormal pressure thereon is produced—in a manner presently to be explained—the spring 19^b which controls the stop will yield and permit the stop to be depressed whereby the abutment will pass by said stop.

As a means for actuating the slide 15, I have shown a hand-operated device comprising a segmental member 20 fast on a horizontal shaft 21 suitably journaled in one of the legs of the machine-frame and a flexible or chain-connection 22 between said slide 15 and the segmental member 20, and which connection passes over sheaves or pulleys 23, 24 mounted on the top-plate adjacent to the slide. Suitably keyed to the shaft 21 is a hand-lever 25. By the means just described, the slide 15 is actuated in one direction to cause the supporting-frame to be rotated. It will be seen that, thereby, the frame is actuated intermittently; that is, in a step-by-step manner. To return the slide to starting position, a chain or connection 26 is secured at the end of the slide opposite to that to which chain 22 is attached, and passes over a pulley or sheave 27. At its end is attached a weight 28. When, therefore, the operator moves the hand-lever 25 in the direction opposite to that indicated by the arrow in Fig. 4, the slide, under the influence of the weighted connection 26, will with certainty be shifted back to normal position. Any overthrow movement of the frame when rotated by the hand-lever is precluded by the engagement of one of the abutments with the stop 19, as already explained.

The frame 4 constitutes a support for one or more equidistantly-arranged hosiery drying and shaping members 29. In the preferred embodiment of the invention, there is a series of these members, and each is preferably removably attached in any appropriate manner to the circular-member 5 so that it may be replaced by another of 115 different size whenever necessary. These members may be mounted on said member 5, and I prefer to dispose them so that they will have their edges extending parallel to their direction of travel, as shown in Figs. 120 1-9; or, in lieu of this arrangement, they may be placed at an angle, as shown in Figs. 10 and 11.

Referring now to Figs. 8 and 9, it will be seen that each of the stocking-holding and 125 shaping members 29 is hollow, and is formed relatively narrow in cross-section and has its two edges 29^a relatively thin. By reason of this peculiar construction, the article is creased and shaped,—the narrowness of the 130

body of the member and the thinness of the edge contributing to this result. These stocking-holders or members 29 are formed by joining two side sections 29^b at their edges, and have a central partition which divides the holders into two channels 29^c and 29^d, which, near the toe-end 29^e, communicate with each other. There is thus presented a continuous passage for a heating or drying medium extending from the open end of the holder to the toe-end and back again to the open end. These holders are preferably made of some good heat-conducting material like copper. At their open end, these holders are provided with a flanged base-piece 29^f, elliptical in form, which forms a means of attachment of the holders to the upper face of the circular member 5. They are attached in any suitable manner and others of different size or form may be substituted therefor. To the end, first, that these holders may be supplied with a heating or drying medium of a predetermined temperature and in a predetermined volume, and, then, that such heating or drying medium—after circulating through said channel and chambers 29^c and 29^d—may be withdrawn from or be conveyed off from the holders, I provide the means for effecting these results, to-wit: The circular member 5 is provided with a pair of annular channels 30 and 31, the former being what I shall designate the "supply-chamber," and the latter the "exhaust-chamber." These chambers or channels extend entirely around the circular-member. They are, of course, independent of each other. That which I have designated the supply-chamber communicates as by a port 30^a with the open end of the channel 29^c in the stocking-holder 29, while the exhaust-chamber communicates, as by a port 31^a, with channel 29^d in each of the equidistantly-disposed holders 29. To convey the heating or drying medium into the supply-channel or chamber, as from a suitable source of supply or generation—and I may here state that said medium may be steam, hot air or water, or any other appropriate thermal element—I connect with said supply-chamber, by means of flexible couplings 30^b, in the form of a packing nut, a series of pipes, tubing or the like, (designated by the numeral 32) each of which connects at its opposite end 33 with the hollow hub-member 7 which is common to all of said pipes. The packing nuts 30^b constitute a flexible connection, whereby expansion is taken care of. Leading into the top of said chambered hub-member is a supply-pipe 34 which extends upwardly to and through the upper covered frame-work of the machine and connects with a suitable source of supply or generator. Encircling this pipe 34 here it enters the hub-member is a stuffing-

gland or packing nut 35 which constitutes a steam-tight connection between the pipe 34 and hub-member, and which subserves, also, the function of overcoming the difficulties that would otherwise occur by reason of expansion. To exhaust the steam or other heating agent from the exhaust-chamber—after it has circulated through the holder—a pipe or tubing 36 is connected therewith at one end, and has its other end connected 75 with the lower hub-member 8 which is chambered and provided with an outtake pipe 38 leading back to the generator, or allowed to escape. This hub-member 8, like the member 7, is provided with a stuffing 80 gland to insure a steam-tight connection between it and the outtake pipe 38.

By referring to Figs. 1 and 2, it will be seen that the pipes 32 are coupled to the inner side walls of the circular member 5 so 85 that they may feed into the supply-channel; and that the couplings of the pipes 36 extend through said supply-channel and into the exhaust-channel. These channels may be partitioned off at intervals to form 90 sub-chambers 37, 37^a, and each of the pipes 32 and 36, may respectively supply steam to and exhaust it from each of these sub-chambers. In this arrangement a pair of the hosiery-holders would communicate with 95 these sub-chambers 37 and 37^a. At times, and especially when the machine is to be started and when it is stopped, it is necessary to drain off the excess of condensation: For this purpose, a series of small 100 drainage-pipes 39 are connected with the circular-member 5, and these are controlled by valves 40.

The structure which has been described in the foregoing is adapted to present a drying 105 medium to the inside of hosiery and the like; that is to say, when one or more of the articles, such as stockings, has been positioned on each of the hosiery-holders, and the drying medium is permitted to circulate 110 through said holders (by the several instrumentalities already specified), the steam, etc. will cause these holders to become heated and effect a rapid evaporation of the moisture in the article. The heat is, thus, applied to the inner surface of the article. I find it of advantage to subject the external surface to a drying medium, also, and, preferably, simultaneously with its application to the internal surface. For this purpose, 120 the following structure may be provided: Secured to the base, beyond the outside edge of the circular member 5, is a series of outwardly-extending brackets 41 to which are attached the lower ends of outside uprights 125 or stanchions 42. Secured to the upper ends of these stanchions are inwardly and upwardly-extending supports 43 which terminate in a ring 44 having an upstanding vapor-escape tubular member 45, connecting 130

with a suitable exhaust-system whereby the moisture and vapor rising from the drying of the hosiery may be quickly removed. Suitably secured to each of the outer stanchions 42 is a fabric or other heat-resisting material 47 which forms the outer wall of the housing or casing. The top or roof of the housing is similarly formed. It will also be seen that this annular housing is in the path of travel of the upstanding hosiery-holders and is adapted to retain heat (supplied to it in any desirable manner, as by the emanation or radiation from the hosiery holders or from the holder-carrier 5) while the heating medium passes through them from the steam pipes, etc., whereby the external surface of the hosiery or like article is subjected to a drying action. The housing-wall also subserves the function of protecting the operator from the intense heat of the machine.

As shown in Fig. 2, the circular housing or casing, at the front portion of the machine, is interrupted by end-walls 48 and 49, and these are connected by an arcuate wall 50. Each of the walls 48 and 49 is provided with an elongated entry opening 48^a and an exit opening 49^a, respectively, through which the hosiery-holders may pass. These openings are of such size and form as to reduce to a minimum the escape of the heat contained in the working space 51 of the housing. The lower ends of the walls 48 and 49 extend to a point just above the plane of the circular member 5 which passes under these walls sufficiently close to preclude any appreciable escape of the contained heat.

Operation: Initially, the operator will actuate (by means of the operating mechanism already detailed, and including the hand-lever at the front of the machine which effects movement of the pawl-carrying slide) the circular member 5 to bring into the open space 51, between the walls 48 and 49, a series—preferably four—of the hosiery-holders, whereupon each holder has placed on it the hosiery article. Thereafter, he actuates the circular holder-carrier 5 one space, and places on the newly-presented holder one of the articles; and so on until he fills the series of holders. In the meantime, the first-filled holders have entered the heat-containing casing or housing, and the drying-medium has heated the holders themselves, so that both the internal and external surfaces are heated. By the time the first holder has made the circuit and is brought into the filling-space 51, the article thereon will be thoroughly dried and, by reason of the specified form of the holder, it will simultaneously have been shaped. The operator, or his assistant, then removes these dried and shaped articles from each of the holders and lays them on an adjacent pressing-board 65 (not shown).

The structure which has hereinabove been described is the preferred form of machine. In Figs. 10 and 11, I have illustrated a modified form of structure. The modification resides, among other things, in arranging the 70 hosiery-holding-members at an angle to the line of their travel. This arrangement necessitates a different form of end-walls of the heating-housing, and this construction I will now describe: In lieu of stationary 75 end-walls, such as those described in connection with the preferred structure, I may provide a pair of cam-operated doors or gates 52 and 53 at each side of the space 51: In this instance, each gate 52 carries a pivot 80 52^a which turns in a bracket 52^b mounted on a stationary part of the machine. Each door 53 rotates on a pivot 53^a formed in a bracket 53^b, also mounted on a stationary part of the machine. The position of these gates is 85 controlled by cam-surfaces: As seen in Fig. 10, each gate 52 is provided with an extension 52^c which carries a roller 52^d adapted to engage a cam-surface 54 (Fig. 11). When the roller rides into one of the depressions 90 54^a, the gate is closed; but, as the roller rides along the outwardly-extending and more sharply defined portion of the cam-surface, the gate 52 is thereby caused to swing toward the right (as viewed in Fig. 11). Then, as 95 it traverses the elongated portion of the cam-surface, the tendency of the gate is to swing toward the left and close. Means (not shown) may be provided to maintain the roller against the cam-surface, if necessary; but, in practice, that has not been found essential. The part 53^c of the gate-actuating element 55 carried by the gate 53 is provided with an arcuate slot in which moves a roller 53^d adapted to traverse a 100 cam-surface 56, and by which each of the gates 53 is alternately opened and closed. The cam-surfaces 54 and 56 are so formed and relatively arranged that the gates 52 and 53 at each side of the space 51 are 105 simultaneously opened so that each hosiery-holding member may pass therethrough, after which the gates close.

In the modified form of structure shown in Figs. 12 and 13, there is disclosed power-driven mechanism for actuating the circular member 5, as already referred to: In this instance, the ring 5 is provided with a rack 57 with which meshes a vertically-disposed pinion 58 fast on a stub-shaft 59 suitably 110 journaled in bearings 60 in a bracket 61 mounted on the base of the machine. Loosely mounted on said shaft 59 is a pulley 62 which is driven by a belt 63 deriving motion from a suitable source of power. 115 The pulley may be clutched to the shaft by any suitable means. By way of example, I have shown a clutch-device 64 operated through a hand-lever 65 by the operator whenever it is desired to effect a traveling 120

movement of the machine to carry the hosiery-supporting holders into the casing. It will be understood that when the pulley and shaft are clutched, the pinion 58 is revolved and, as it meshes with the rack 57, as aforementioned, it will cause the circular member 5 to travel. The circumference of the pinion is preferably equal to the distance which one of the hosiery-holders must travel 10 to move from the filling-space 51, through the opening 48°, and into the heat-containing housing or casing.

By the structure just described, I have provided power-driven actuating-means, 15 which may be utilized in lieu of the manually-operated mechanism previously described.

While I have herein described my invention in detail and illustrated two embodiments thereof, it is nevertheless to be understood that I do not limit myself to such details, nor to these two embodiments; since the invention is susceptible of a wide range 20 of modification without departing from its 25 spirit.

What I claim is:

1. An apparatus for drying and shaping textile hosiery articles including in combination, a base, a support mounted thereon, 30 one or more hollow article-holding and shaping members mounted on said support and each being narrow in cross-section relatively to its width and having its opposite sides converging at their margins to form 35 edges substantially sharpened to effect the formation of a crease in and shaping of the article, and means for maintaining a heating medium in the interior of said hollow member or members to heat the member or 40 members from within and thereby effect evaporation of moisture from the article sustained by said member.

2. An apparatus for drying and shaping moistened hosiery articles including in combination, a support, a channeled article-holding and shaping member mounted on 45 said support and being narrow in cross-section relatively to its width and having sides converging into an edge substantially sharpened to effect the formation of a crease in and a shaping of the article, and means for maintaining a heating medium in the channel of said holding and shaping member to heat the same from within and effect evaporation of moisture from the article sustained by said member.

3. An apparatus for simultaneously drying and shaping hosiery including in combination, a base, a supporting-instrumentality mounted thereon, a combined drying and shaping device mounted on said instrumentality and comprising a plurality of narrowly-spaced sides connected at their edges to form a heat-containing member and 55 converging into sharpened edges to produce

a crease in said hosiery, and means for maintaining a heating medium within the interior of the device.

4. An apparatus for simultaneously drying and shaping hosiery including in combination, a base, a support mounted thereon, 70 a hollow, combined drying and shaping member formed thin in cross-section and having its sides converging and substantially reduced to form sharpened edges for 75 effecting the formation of a crease in the hosiery, and means for supplying a heating medium to said hollow member to heat the interior thereof.

5. The combination, in hosiery drying and 80 shaping apparatus, of a support, a metallic heating and shaping form thereon relatively thin in cross-section and having oppositely-disposed sides converging at their margins to form crease-producing edges and provided with channels for the passage of a 85 heated fluid, and means for supplying heated fluid to the interior of said form, whereby the article mounted thereon may simultaneously be dried and creased.

6. An imperforate, channeled hosiery-drying and shaping form to which the hosiery is directly applied, said form being relatively thin in cross-section and having opposite sides meeting at an acute angle and presenting substantially sharp edges, and provided with a passage to contain a heating medium whereby the form may be heated and hosiery simultaneously dried, shaped 90 and creased thereby.

7. An imperforate stocking drying and shaping form to which the stocking is directly applied, said form being provided with an elongated heat-conveying passage adapted to receive a heating medium for 105 heating the same from within and being relatively thin in cross-section and having opposite sides meeting at an acute angle and presenting substantially sharp edges, whereby the stocking will be simultaneously dried, 110 shaped and creased.

8. As an article of manufacture for use in apparatus for simultaneously drying and shaping hosiery and the like, a combined drying and shaping member formed thin in 115 cross-section and having its sides converging to form substantially sharpened crease-producing edges and hollow to contain a heating medium for heating the member from within.

9. As an article of manufacture for use in apparatus for simultaneously drying and shaping hosiery, a combined drying and shaping member formed with a relatively narrow body and with sides meeting in an 125 acute angle to present oppositely-disposed, substantially sharpened crease-producing edges and hollow to contain a heat-producing medium for heating the member from within.

10. As an article of manufacture for use in apparatus for simultaneously drying and shaping hosiery and the like, a combined drying and shaping member formed with a relatively narrow body and with converging sides to form oppositely-disposed, substantially sharpened crease-producing edges, said member being provided with an internal channel to contain a heating medium.
10. 11. The combination, in stocking drying and shaping apparatus, of a steam conduit; and a hollow metal form having its interior in communication with said conduit, the said form being relatively thin in cross-section, having substantially sharpened crease-producing edges, and being channeled internally for the passage of a heating medium, whereby a stocking may be simultaneously dried, creased, and rendered substantially flat when dry.
12. An apparatus for drying and shaping textile hosiery articles including in combination, a support, a hollow article-holding and shaping member mounted on said support and being narrow in cross-section relatively to its width and having its opposite edges substantially sharpened to effect the formation of a crease in and a shaping of the article, and means for supplying a heating medium to the interior of said shaping member for heating the same from within and thereby effecting evaporation of moisture from the article sustained thereby.
13. An apparatus for simultaneously drying and shaping hosiery including in combination, a heat-conveying support, a combined drying and shaping device mounted on said support and comprising a hollow heat-containing and shaping member having narrowly spaced sides which converge to form substantially sharpened edges to shape the article substantially flat and to crease the same at opposite edges, and means for supplying a heating medium to the interior of said member to effect the heating of the same from within.
14. The combination, in a drying device, of a hollow form adapted to be heated from within and having sides which converge to form substantially sharpened edges for simultaneously drying and shaping moistened textile hosiery articles, a table upon which said form is supported, an inlet and an outlet in said form for the circulation of a heating medium, a partition within said form providing spaces for containing the heating medium and communicating with said inlet and outlet, and piping communicating with said inlet and outlet.
60. 15. The combination, in a drying device, of a hollow hosiery drying and shaping form adapted to be heated from within and having crease-producing edges, a table for supporting said form, said form having an inlet and an outlet for the circulation of a heating medium, a partition within said form providing spaces for containing the heating medium and communicating with said inlet and outlet, and piping communicating with said inlet and outlet.
- heating medium, a partition within said form providing for the passage of the heating medium and communicating with said inlet and outlet, and a plurality of heat-conveying instrumentalities independently connected to said inlet and outlet whereby said form effects a drying and simultaneous flattening of the hosiery article placed thereon.
16. The combination in a hosiery drier, of a heat-containing chamber, a form-support adapted to occupy a position within the chamber, a hosiery form mounted on said support and having substantially sharpened crease-producing edges and hollow to contain a heating medium to heat the form from within, and means for introducing the heating medium into the hollow portions of said form, whereby the article mounted thereon may be simultaneously dried, shaped and creased.
17. The combination in a hosiery drier, of a heat-containing chamber, a form-support adapted to occupy a position within the chamber, a heat-holding hosiery-shaping form mounted on said support and relatively thin in cross-section and having substantially sharpened crease-producing edges and hollow to contain a heat-producing medium to heat the form from within, and means for causing said heat-producing medium in said form to effect a heating of the form from within, whereby the article mounted thereon may while in said chamber be simultaneously dried, shaped and creased.
18. In apparatus for treating hosiery and the like, a series of metallic drying and shaping forms, each relatively thin in cross-section and having its sides converging to form substantially sharpened edges and hollow to contain a heating medium to cause the form to be heated from within, and a support for and common to all of the series, said support including means for supplying a heating medium to the interior of the forms whereby a plurality of stockings may be dried and simultaneously shaped.
19. In apparatus for drying and shaping hosiery, a heat-conveying instrumentality, and a series of hosiery-holding forms juxtaposed on said instrumentality and channeled for the passage therethrough of a heating medium for heating the form from within, each relatively thin in cross-section and having its sides meeting at an acute angle to present substantially sharpened edges, whereby hosiery may be simultaneously dried and shaped.
20. In apparatus for drying and shaping hosiery, a heat-conveying instrumentality, a series of hosiery-holding forms juxtaposed on said instrumentality and relatively thin in cross-section and having substantially sharpened edges and chambered for

5 containing a heating medium to heat the form from within, whereby hosiery may be simultaneously dried and shaped, and a table upon which said heat-conveying instrumentality is supported.

10 21. The combination, in a drying device, of a hollow form, a table, a casting carried by the table and connected to said hollow form, an inlet and an outlet in said casting for the circulation of a heated fluid, a partition within said form providing independent spaces communicating with said inlet and outlet, and a pair of pipes independently connected to said inlet and outlet.

15 22. A drying mechanism for hosiery and like tubular fabrics, comprising a pair of pipes, connecting fittings for said pipes, each provided with a plurality of passage-ways with spaced-apart vertical exits 20 through the upper wall of the fitting, and hollow vertically-partitioned formers each secured to one of said fittings and forming a communicating passage-way between said spaced-apart exits.

25 23. The combination, in a drying device, of a hollow form having sides meeting at an acute angle to present crease-producing edges, a table, a casting carried by the table and connected to said hollow form and having an inlet and an outlet for the circulation of a heated fluid, a partition within said form providing communicating spaces connected with said inlet and outlet respectively, and a plurality of conduits independently 30 connected to said inlet and outlet, respectively.

35 24. A drying mechanism for hosiery and like tubular fabrics, comprising a plurality of juxtaposed steam-pipes, connecting fittings for said pipes, a member provided with sections having engagement with the pipes and having spaced-apart vertical exits 40 through the upper wall thereof, and hollow vertically-partitioned formers, each former being relatively thin in cross-section and having substantially sharpened crease-producing edges and each secured to said member adjacent said fittings and forming a 45 communicating passage-way between said spaced-apart exits.

50 25. An apparatus for drying and shaping hosiery articles including in combination, a base, a supporting-member movably mounted thereon, means for effecting movement of 55 said member, one or more hollow article-holding and shaping members mounted on said supporting member and traveling therewith and each being narrow in cross-section relatively to its width and having its opposite sides converging at their margins to 60 form edges substantially sharpened to effect the formation of a crease in and a shaping of the article, and hollow to contain a heating medium for heating the member from within, said supporting member being chan-

neled and constituting means for supplying a heating medium to the interior of said holding and shaping member to effect evaporation of moisture from the article sustained by said member.

70 26. An apparatus for simultaneously drying and shaping hosiery including in combination, a base, a traveling support mounted thereon, a plurality of hollow, combined drying and shaping members carried by the support and formed relatively thin in cross-section and having sides meeting in substantially reduced crease-producing edges, and means for supplying a heating medium to the interior of said hollow members.

75 27. The combination in a hosiery drier, of a drying chamber, a carrier, a hollow hosiery form mounted on said carrier and partitioned to form passages for a heating medium to heat the form from within, and means for traversing the said carrier into and through the drying chamber.

80 28. The combination in a hosiery drier, of a drying chamber, a table, a guiding device on the table and in juxtaposition to the drying chamber, a carrier, a series of hollow and channeled stocking forms thereon and adapted to travel with the carrier into the drying chamber and to be heated from within, means for traversing the carrier, and means for constantly supplying a heating medium to the interior of each of said forms during a period of their travel.

85 29. The combination of a table, a guiding device thereon, a carrier on the device, means for traversing the carrier, and a hosiery form mounted on the carrier and having sides converging to form crease-producing edges, and hollow to contain a heating medium whereby the form may be heated from within.

90 30. The combination of a table, a guiding device thereon, a carrier adapted to the device, a housing provided with inlet and outlet openings, a hosiery-shaping form on the carrier having sides meeting at an acute angle to present substantially sharp crease-producing edges and hollow to contain a heating medium for heating the form from within, and means for traversing the carrier into and out of said housing through said 95 openings.

100 31. An apparatus for simultaneously drying and shaping hosiery, including in combination, a base, a traveling supporting-frame 105 movably mounted on said base, means for moving said frame on its supporting-base, a heat-containing housing also mounted on said base, a hosiery drying and shaping member carried by said supporting-frame 110 and traveling therewith into and out of said housing and hollow to contain a heating medium for heating the member from within, and means for supplying the heating medium to the interior of said shaping member.

32. An apparatus for simultaneously drying and shaping hosiery, including in combination, a base, a traveling supporting-frame movably mounted on said base, means for moving said frame on its supporting-base, a heat-containing housing also mounted on said base, a combined drying and shaping member formed with two oppositely-disposed substantially sharpened crease-producing edges and carried by said supporting-frame and traveling therewith into and out of said housing and hollow to contain a heating medium for heating the member from within, and means for supplying the heating medium to the interior of said shaping member.

33. An apparatus for simultaneously drying and shaping hosiery, including in combination, a base, a rotatable supporting frame movably mounted on said base and channeled for the passage of a heat-producing medium, means for moving said frame on its supporting-base, a heat-retaining housing also mounted on said base, and a combined drying and shaping member carried by said supporting-frame and traveling therewith into and out of said housing and hollow to receive the heating medium from said frame for heating the member from within and thereby to effect evaporation of moisture from an article mounted on the exterior of the form.

34. An apparatus for simultaneously drying and shaping hosiery articles, including in combination, a base, a rotatable support mounted thereon, actuating means therefor, a series of hollow and narrow thin-edged drying and shaping members mounted on said rotatable support, means for supplying a heating medium to the interior of each member of the series to heat it from within to an appropriate drying temperature, and a heat-retaining housing disposed relatively to the path of travel of said shaping members and into which housing said members are positioned.

35. An apparatus for simultaneously drying and shaping hosiery-articles, including in combination, a base, a rotatable support mounted thereon, actuating means therefor, a series of relatively narrow-bodied, sharpened-edged drying and shaping members mounted on said rotatable support and hollow to receive a heating medium for heating the members from within, means for supplying the heating medium to the interior of each member of the series to heat it to an appropriate drying temperature, and a heat-containing housing disposed relatively to the path of travel of said shaping members and wherein heat is retained for application to the exterior surface of the article, said housing being provided with entry and exit openings through which said members pass.

and formed in part of a material for retaining the heat within the housing and for preventing it from burning the operator.

36. An apparatus for simultaneously drying and shaping hosiery-articles, including in combination, a base, a rotatable support mounted thereon, actuating means therefor, a series of narrow-bodied, sharpened-edged drying, shaping and creasing members mounted on said rotatable support and hollow to contain a heating medium for heating the members from within, means for supplying a heating medium to the interior of each member of the series, a heat-retaining housing disposed relatively to the path of travel of said shaping members whereby heat is retained and applied to the exterior surface of the article, said housing being provided with entry and exit openings through which said members pass into and out of said housing, and with gates for closing said openings.

37. An apparatus for simultaneously drying and shaping hosiery-articles, including in combination, a base, a rotatable support mounted thereon, means for effecting intermittent movement of said support, a series of relatively narrow-bodied and sharpened-edged drying and shaping members on said support and hollow to contain a heating medium, means for introducing a heating medium into each member of the series to heat it from within, and a heat-retaining housing into and out of which said members are moved during the travel of said support.

38. An apparatus for simultaneously drying and shaping hosiery articles including in combination, a base, a rotatable support mounted thereon, a series of relatively narrow-bodied and thin-edged drying and shaping members disposed on said support, said support being provided with channels for supplying a heating medium to the members and thereby to the interior surface of the hosiery articles, and heat-conveying and exhausting-pipes connected to said channels, respectively, means for draining said supply channels, and a heat-retaining housing into which said members are moved and wherein said articles are dried on their exterior surface.

39. A device for drying and finishing moistened hosiery comprising a steam-heated metallic form having a substantially sharpened edge to shape, crease and finish the article mounted thereon simultaneously with its drying when heated from within and provided with a passage for a heating medium.

40. A stocking mold for simultaneously drying, shaping and finishing in stoned hosiery comprising a hollow, metallic form having its sides converging and its edges substantially sharpened to crease and finish

the article mounted thereon simultaneously with its drying when the form is heated from within.

41. A stocking mold for simultaneously drying, shaping and finishing moistened hosiery comprising a hollow, metallic form having its sides converging and its edges substantially sharpened to crease and finish the article mounted thereon simultaneously with its drying when the form is heated from within, and means for maintaining heat in the form to heat it from within.

42. A hosiery drying and shaping device comprising a solid heating body having a steam-passage, and a steam-supplying structure outside of the body and communicating with the passage to heat the device from within, the sides of said device converging into substantially sharpened edges to effect increasing of the hosiery-article thereon simultaneously with its drying.

43. In hosiery finishing apparatus, a metallic device having its sides converging to form sharpened edges and functioning simultaneously to dry, crease and finish the

article mounted on the exterior thereof when the form is heated from within, and means for maintaining heat within the device.

44. A hosiery drying and shaping form having its sides relatively thin in cross-section and converging to present substantially-reduced edge-portions, and a partition dividing the form into a plurality of chambers for containing a medium to heat the form from within.

45. A drying and shaping form for hosiery comprising a body-portion relatively thin in cross-section, and edge-portions which converge to present substantially-sharpened edges, said form being hollow to contain a medium adapted to heat it from within, and a base-portion provided with inlet and outlet-ports.

In testimony whereof I affix my signature in presence of two witnesses.

GEORGE COLLIS.
